US0D1057873S

(12) **United States Design Patent** (10) **Patent No.:** **US D1,057,873 S**
(45) **Date of Patent:** **** Jan. 14, 2025**

(54) **PICKLEBALL PADDLE**

(71) Applicant: **Shenzhen Rock Network Technology Co., Ltd.**, Guangdong (CN)

(72) Inventor: **Junlin Zeng**, Guangdong (CN)

(**) Term: **15 Years**

(21) Appl. No.: **29/903,821**

(22) Filed: **Sep. 28, 2023**

(51) **LOC (15) Cl.** **21-02**

(52) **U.S. Cl.**

USPC **D21/731**

(57) **CLAIM**

The ornamental design for a pickleball paddle as shown and described.

DESCRIPTION

FIG. 1 is a perspective view of the pickleball paddle showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures illustrate portions that form no part of the claimed design.

1 Claim, 8 Drawing Sheets
